Specification for Design.

Patented Mar. 9, 1920.

Application filed September 26, 1919. Serial No. 326,696. Term of patent 3½ years.

To all whom it may concern:

Be it known that I, EDWIN H. WEBER, a citizen of the United States, residing at Meriden, county of New Haven, and State of Connecticut, have invented a new, original, and ornamental Design for a Chandelier, of which the following is a specification, reference being had to the accompanying drawing, forming a part thereof.

In said drawing:

The figure is a perspective view of an ornamental chandelier embodying the design of my invention.

I claim—

The ornamental design for a chandelier substantially as shown.

EDWIN H. WEBER.
